HEARSE

Harry A. Toulimin, Jr., Dayton, Ohio, assignor to
 Commonwealth Engineering Corporation, Wil-
 mington, Del., a corporation of Delaware

Application March 27, 1939, Serial No. 264,299

10 Claims. (Cl. 214—83)

This invention relates to vehicles and in particular to hearses, and means of supporting caskets in hearses and moving the casket into and out of the hearse.

5 It is an object to provide a side loading hearse in which the casket can be loaded into or delivered from the hearse through either side thereof.

10 It is a further object to provide mechanism for this purpose which eliminates all guide tracks and similar mechanism.

15 It is an additional object of this invention to provide means by which the table supporting the casket, with the casket, can be moved from a longitudinal position to a transverse position about a central axis within the confines of the casket and the table so that the rear end of the table and casket will not engage the wall of the hearse opposite to that through which the casket moves.

20 It is an object to provide a mechanism and a method for moving a casket-supporting table with or without a casket thereupon, through a side door opening of materially lesser width than the length of the table or casket.

25 In particular it is the object of this invention to provide a table rotatable around a vertical axis arranged on the center line of the table and optionally closer to one end of the table than the other.

30 It is a further object to provide means of moving the table bodily from a central position, longitudinally aligned with the major axis of the hearse, to a position with the center of the table off-center of the major axis of the hearse.

35 It is an object to provide means of simultaneously or successively rotating the table after its longitudinal axis has been thus displaced or while it is being so displaced.

40 It is the primary object of this invention to provide a table in the hearse which rotates about its vertical axis and successively or simultaneously or previously is moved towards one wall of the hearse.

45 It is a further object to place the center of such rotative movement closer to one end of the table than the other and preferably closer to the end that emerges from the hearse last or remains in the hearse. Heretofore, rotatable tables have not been employed, although desirable because of the simplicity of the construction and movement and because of the elimination of any guide tracks in the floor of the hearse. The reason such rotatable tables have not been employed has been that when the table was rotated, with or without the

casket, in order to get the forward end through one side of the hearse, the rear end of the table and casket would strike the other side of the hearse, preventing further rotating and preventing exit of the table and casket. The present invention obviates this heretofore insurmountable difficulty by first moving the table bodily laterally towards the wall of the hearse through which the table is to project. Then, according to this invention, simultaneously with such movement or after it has been performed, the rotation of the table about its central vertical axis takes place. In this way, the table and casket can be rotated on the vertical axis without the rear ends striking the opposite wall of the hearse. 15

It is a further object to provide fully automatic electrical means for moving the table in or out through either side door of the hearse, which is put into operation by merely pressing appropriate button switches and which operates with a minimum of noise whereby the casket may be moved into or out of the hearse through the side door with the proper dignity.

Still another object is to provide a modified form of table operating means whereby the necessity for using a reversible operating motor is overcome.

Still another object is to provide a modified form of fully automatic electrically controlled operating means for moving the casket supporting table hydraulically, thereby adding still further to the quietness of operation while obtaining the other advantages of hydraulic operation.

It is a further feature of this invention that by placing this center of rotation towards the rear of the table, this movement is facilitated.

Furthermore, it is possible by this invention to optionally unload the casket through the rear of the hearse. 40

In the drawings:

Figure 1 is a diagrammatic plan view, with the hearse walls in section, of the floor of the hearse and the table and casket disposed thereabove, showing the doors provided at each side and at the rear through which the table and casket are moved.

Figure 2 is a reduced diagrammatic plan view showing the position of the table and casket partially extended through a side door opening. 45

Figure 3 is a similar plan view showing the table and casket in their fully extended position.

Figure 4 is a vertical section, taken on the line 4—4, looking in the direction of the arrows, of Figure 1, showing the operating mechanism for 50 55

laterally shifting and rotating the table and casket.

Figure 5 is a section on the line 5—5, looking in the direction of the arrows, of Figure 4.

Figure 6 is a view showing diagrammatically the electrical means for controlling the operating motor employed in Figures 1 to 5.

Figure 7 is a view similar to Figure 4, but showing a modified form wherein two non-reversible operating motors are employed.

Figure 8 is a similar view showing another modification wherein two non-reversible operating motors are employed.

Figure 9 is a view showing diagrammatically the electrical means for controlling the operating motors of Figure 7.

Figure 10 is a bottom plan view of hydraulically operated means for moving the table.

Figure 11 is a view showing diagrammatically the electrical means for controlling the operating means of Figure 10.

Referring to the drawings in detail, reference numeral 1 designates generally the rear portion of the body of the hearse, having the customary floor 2 and having a door 3 at the rear through which the casket-supporting table 6 and/or the casket 7 may be moved if desired. Located in the right-hand side of the rear of the hearse is a door 4 which is hinged in the usual manner to the side wall. Located in the left-hand side is a similar door 5. These doors 4 and 5 are located so that the table 6 and casket 7, when in their final transverse position shown in Figure 3, will clear both sides of the opening. The doors are relatively narrow, being considerably narrower than the length of the table and casket, their exact width and location being determined by the width of the table, the width of the interior of the rear of the hearse, the location of the point about which the table 6 is pivoted and the manner in which the table is moved into and out of the hearse. If desired, a single side door on one side only of the hearse may be employed.

The floor 2 of the hearse is provided with a transverse slot 8 through which projects the turret or standard 9 which forms a pivotal support for the casket carrying table 6. This table is mounted upon casters 10 that rest on the surface of the floor 2.

50 The pivot member 9 is connected to or integral with gear 11 which engages with a rack 12 mounted at either end on brackets 13 beneath the floor 2. This pivotal member 9 and the gear 11 are engaged by pin 14, which extends through the gear 11 and into the member 9 and is integrally connected with and formed as a part of the worm nut 15, which is threaded upon the worm 16. This worm 16 is pivotally supported by brackets 17 at either end beneath the floor 2.

60 In the form shown in Figures 1 to 6, the left hand end of worm 16 has mounted thereon a worm gear 18 which is in turn engaged by a worm 19 on the armature shaft 20 of the reversible motor 21.

65 In all of the forms shown in the drawings, limit switches 22, 23, and 24 are so disposed as to appropriately control the operation of the device in a manner which will presently appear. Limit switch 22 is normally closed and is opened by the turret 9 reaching the end of its travel to the left in slot 8. Limit switch 23 is normally closed and is opened by the turret 9 reaching the extreme right-hand position shown in Figure 3. Limit switch 24 is open when the turret 9 is in 70 the neutral position of Figure 1 and is closed

when turret 9 leaves this neutral position. Button switches 25 and 26 are provided (Figures 1 and 6) on the inside of the right-hand side of the hearse for control of the movements of the table through door 4 and a similar pair of button switches 27 and 28 are provided on the left-hand side of the hearse for controlling movement of the table in and out of the opening made by door 5.

Referring to Figure 6 which shows the electrical connections for use with the form of Figures 1 to 5, assume that the table 6 is in the running position of Figure 1, and it is desired to move it out of the right hand door opening. The operator presses button switch 25 which causes winding 35 of solenoid 29 to move its armature and rod 37 upwardly, thereby closing contacts 30, 31, 32 and 33. Current thereupon flows through the field winding 34 of motor 21 and through the armature winding thereof in such direction as to move nut 15 to the right, thereby beginning to move table 6 transversely to the right and at the same time causing rotation of turret 9 and table 6 by means of gear 11 engaging rack 12. The operator holds button switch 25 closed only long enough for the table to begin to move, whereupon limit switch 24 which was held open by turret 9 is closed and maintains coil 35 of solenoid 29 energized through contact 36, limit switch 23 being closed. The operator 40 may then release button switch 25 and the motor 21 will continue to move the table out the right-hand side of the hearse, until turret 9 reaches the end of slot 8 when it strikes limit switch 23, opening it, thereby breaking the circuit to coil 35 38 of solenoid 29, and causing motion-transmitting rod 37 to be moved to the neutral position shown in Figure 6, by reason of springs 38, thus breaking the circuits established by contacts 30, 31, 32 and 33 and stopping rotation of motor 21. 40

With the table in the position of Figure 3, if it is desired to move it within the hearse, the operator presses button switch 28 for an instant sufficiently to energize coil 39 of solenoid 29. Armature 29 then causes rod 37 to move downwardly (Figure 6), establishing circuits through contacts 40, 41, 42 and 43, current now being supplied to the field 34 of motor 21 in the same direction as before, and to the armature winding in a reverse direction so that motor 21 rotates in a 50 direction such as to move nut 15 and the associated turret and table towards the center of the hearse. This motion continues until the table is in the running position of Figure 1 when it is stopped by the action of turret 9 striking limit switch 24 which opens the circuit to solenoid coil 39 established by contact 44 thereby causing rod 37 to return to the center position and stopping motor 21. 55

Similar mechanism is provided for moving the table in and out of the opening provided by door 5, switch 27 being employed to move the table out of the door, switch 28 to move it in from the position where it projects out door 5, and limit switch 22 being opened by turret 9 at the limit of 65 its travel to the left in slot 8 whereby to stop motor 21.

Describing now the modification shown in Figures 7 and 9, there are employed two motors 21a and 21b for operating worm 16, thereby eliminating the necessity for using a reversible motor and eliminating the necessity for using reversing switches for the motor. Motor 21a is adapted to move the table out door 5 while motor 21b is adapted to move the table out door 4. Likewise, 70

motor 21a is adapted to return the table from the position shown in Figure 3 and motor 21b is adapted to return the table from the position wherein it projects out door 5. A dog clutch 45 is disposed between motor 21a and worm 16. Dog clutch 46 is likewise provided between motor 21b and worm 16. These dog clutches 45 and 46 are engaged by solenoids 47 and 48 respectively. Referring particularly to Figure 9, the electrical operation is substantially the same as that discussed above in connection with Figure 8, except that rod 37 in its upward movement establishes a circuit through contacts 49, thereby energizing solenoid 48 and simultaneously causing motor 21b to rotate, thereby moving the nut 18 to the right. Similarly, rod 37 when moved downwardly establishes a circuit through contacts 50 through motor 21a and solenoid 47, thereby causing nut 18 to be moved to the left.

In Figure 8, there is shown a modification wherein two non-reversible motors 21a and 21b operate worm 16. These motors are connected together by a coupling 51, and are so electrically connected that only one of them is in operation at once. Thus motor 21a in Figure 8 is employed to move the table leftward, while motor 21b is adapted to move it rightward in the same manner as described in connection with Figure 7. When motor 21a is energized, motor 21b is not energized and is rotated in a direction opposite to its normal direction of rotation so that worm 16 is moved in accordance with the direction of rotation of motor 21a. Likewise, when motor 21b is driving worm 16, motor 21a is inoperative and is merely rotated idly through coupling 51. For operating the modification of Figure 8, an electrical circuit precisely like that of Figure 9 is employed except that solenoids 47 and 48 are dispensed with.

Referring to the modification shown in Figures 10 and 11, the turret 9 is propelled to and fro along slot 8 hydraulically by means of belt 52 which is fixedly attached to a plate 60a which surrounds rotatable pin 60 projecting upwardly in turret 9 and which passes around rotatable pulleys 53 and 54, being fastened on the side opposite from pin 60 to a stationary member 69 which may be fixedly attached to the chassis of the hearse so as to be immovable. Pulleys 53 and 54 are rotatable about vertical pivoting shafts 55 and 56 respectively. Pivot shafts 55 and 56 are moved laterally by rod 57 which passes through hydraulic cylinder 58 and is integrally attached to piston 59 which slides in cylinder 58. Thus the lateral motion of piston 59 is doubled when transmitted to turret 9 so that turret 9 moves exactly twice the distance through which piston 59 moves and pulleys 53 and 54 are thus prevented from projecting outside the hearse by reason of this motion-doubling construction. Electric motor 21c drives hydraulic gear pump 61 which pumps liquid from tank 62 into valve cylinder 63 through port 72 and thence, depending upon the position of the valves in cylinder 63, into cylinder 58, thereby moving piston 59 and turret 9.

In cylinder 63 there is disposed a rod 64 passing therethrough and upon which are mounted pistons 65 and 66 so that by sliding rod 64, pump 61 is caused to pump liquid either into chamber 67 of cylinder 58 or into chamber 68 thereof. This selective operation is obtained by having ports 70 and 71 so disposed relative to pistons 65 and 66 that the entering liquid from port 72 can be connected either to port 70 or port 71, depending upon the lateral position of rod 64.

When rod 64 is in the position shown in Figure 10, gear pump 61 pumps liquid from port 72 to port 71 and thence into chamber 67. As piston 66 moves to the right, a corresponding amount of liquid is forced out of chamber 68 and returns to reservoir 62 through ports 70 and 71. Similarly, when rod 64 is moved to the right (Figure 10), port 72 is connected with port 70 and port 71, which is now a return port connected to return port 70 which returns the liquid from chamber 67 to reservoir 62. Normally, rod 64 is held in a position such that pump 61 would force liquid into cylinder 67 by reason of spring 73. A solenoid 74 is disposed around rod 64 so that when the electrical circuit is established through solenoid 74, rod 64 is moved to the right (Figure 10), thereby connecting port 72 with port 70 so that pump 61 forces piston 66 to the left (Figure 10).

For operating the hydraulic modification of Figure 10, the electrical circuit of Figure 11 is provided. This circuit is substantially the same as that previously described, motor 21c being non-reversible and being always rotated in the same direction whether the circuit to motor 21c is established through contacts 78 or through contacts 79. When it is desired to move the table leftward with respect to the center line of the hearse, an electrical circuit is established through solenoid coil 80, causing rod 37 to move downwardly (Figure 11) so that the circuit through solenoid 74 is established by contacts 77, so that pump 61 pumps liquid into the cylinder 68, thereby forcing piston 59 and turret 9 to the left with respect to the center line of the hearse. When it is desired to move the table rightward with respect to the center line of the hearse, either by closing switch 25 or 26, the electrical circuit established through coil 80 causes rod 37 to move upwardly (Figure 11), thereby operating motor 21c, contacts 77 remaining open so that rod 64 is in the position shown in Figure 10, whereby fluid is pumped into chamber 67, forcing piston 59 to the right with respect to the center line of the hearse.

An advantage of the invention is that the motion of the table is irreversible so that the table is locked in a given position. Thus table 6 cannot be moved manually by pushing or pulling it and it cannot be dislodged from the running or transporting position shown in Figure 1 by the jars and vibrations attendant upon normal transportation. In the forms shown in Figures 1 to 9, the nut 18 and worm 16 constitute irreversible means for driving turret 9. In the modification of Figures 10 and 11 the piston 59 and consequently turret 9 are prevented from moving laterally by the irreversible gear pump 61 which is driven by irreversible worm 60 and gear 61, so that unless motor 21c is in operative position liquid cannot pass through pump 61. Piston 59 is thus prevented from moving in either direction since liquid cannot be sucked upwardly or forced downwardly through locked (i. e., stationary) pump 61.

As will be understood, gear 61 need be merely a semicircular segment and need not be a full circular gear as shown.

Method of operation

It will be noted, by referring to Figure 1, that the table 6 and its casket 7 are in the at rest position with the longitudinal axis of the table and casket aligned with and coincident on the longitudinal axis of the hearse. The table and

casket are equally disposed from either door or either wall of the hearse. This is the normal carrying and running position of the vehicle.

By reference to Figures 2 and 3, there will be seen the successive positions in unloading and loading that the table and casket will take.

In Figures 2 and 3, a side door 4 has been opened. It will be observed that the door opening is of lesser width than the length of the casket and table. When turret 9 is moved, it is caused to simultaneously move both laterally and rotatably. Thus table 6 and casket 7 are bodily carried towards the right hand open door and side wall of the hearse.

15 The center of pivotal support 9 is disposed upon the longitudinal axis of the table and is located closer to the rear of the table than to the front thereof. As this lateral movement of the table, bodily towards the side wall of the hearse, is taking place, the table and the casket on it begin to rotate on this pivotal center and in so doing, the forward end swings through the door opening left by the open door 4 and the rear end swings toward the opposite side wall and door 5 without 20 striking either because the pivotal point of the pivot 9 has moved towards the opposite side wall.

When the movement is completed, the table and casket are substantially projected through the side of the hearse, in which position the casket can be easily unloaded and in which position a casket can be easily loaded on the table. This compound movement of bodily lateral and rotary movement makes it possible to adopt a pivoted support for a table without having the rear end of the table strike one wall of the hearse or project beyond that wall if the door in that side wall is open.

If it is desired to lengthen the table, the usual pull out slide can be provided on one end thereof so as to furnish an extended support for the casket as it moves from or on to the table during loading.

It will be observed that the casters 10 are ten in number, six of them being located concentrically around the turret 9, thereby giving ample support to the casket and table in the combined lateral shift and rotary movement.

When in running position, the table can be locked by the usual pins, or other devices.

50 If it is desired to unload the casket from the rear end of the hearse, the door 3 is opened. Under such circumstances, it is usual to provide a slide extension on the rear of the table to facilitate unloading the casket.

55 It will be understood that the drawings are purely diagrammatic and not to scale. If desired, a double door or very large single door can be provided, or a folding door on the side of the hearse can be provided so that the door opening is of greater width than the length of the table or casket.

Thus there are important principles in this construction and in the operation thereof:

(a) The bodily movement of the table and casket towards one side of the hearse.

65 (b) The successive or simultaneous rotary movement of the table and casket.

(c) The location of the center pivoting along the axis of the table and casket which can be adjusted so as to regulate the pivotal movement, the swing of the table and the clearance of the table through the door openings.

(d) The irreversible driving means for the table so that it is locked in any given position in which it is stopped which gives a much greater

degree of certainty in loading, unloading and transporting the casket.

(e) The automatically operated movement of the table.

It will be understood that I desire to comprehend within my invention such modifications as may be necessary to adapt it to varying conditions and uses.

Having thus fully described my invention, what I claim as new and desire to secure by Letters Patent, is:

1. In combination, a floor of a hearse, a table freely supported thereon, a parallel rack and worm, a gear engaging said rack, a pivotal support for said table connected thereto, a nut on 15 said worm connected to said gear and pivotal support, and means for rotating said worm whereby said table is caused to move laterally and rotatably.

2. In combination, a hearse floor having a slot 20 therein, a table freely mounted upon said floor, a shaft connected to the bottom of said table projected through said slot, a rack adjacent said slot, a gear mounted on said shaft engaging said rack, a nut mounted on the bottom of said shaft, 25 a worm in said nut arranged parallel to said rack and said slot, and means for actuating said worm for moving said nut therealong and for moving said gear along said rack whereby the table is moved laterally bodily and simultaneous- 30 ly rotated.

3. In combination, a hearse having sides, a door opening in each of said sides, a table mounted upon a floor in said hearse parallel to the sides of the hearse and having its ends projecting 35 beyond the edges of each of said door openings, a pivot for said table disposed within the confines of said table, said table being so proportioned and so disposed with respect to said sides and door openings that it would strike one of 40 said sides if rotated about said pivot, and means for rotating said table about said pivot and simultaneously laterally moving said pivot while preventing substantial longitudinal movement of said pivot in such manner as to project said table 45 through either of said openings while preventing contact of the table with said sides.

4. In combination, a hearse having sides, a door opening in one of said sides, a table mounted upon a floor in said hearse, automatic means for 50 moving said table bodily laterally of the hearse without substantial longitudinal movement thereof and simultaneously rotating said table for thereby moving said table from a carrying position wholly within the hearse to a position 55 where it projects laterally through said opening, and means operated by the lateral movement of said table for rendering inoperative said moving means when said table has attained its projected position.

5. In combination, a hearse having sides, a door opening in one of said sides, a table mounted upon a floor in said hearse, manually initiated automatic means for moving said table bodily laterally of the hearse and simultaneously rotating said table while substantially preventing forward movement thereof and for thereby moving said table from a carrying position wholly within the hearse to a position where it projects laterally through said opening, and means operated 65 by said table when it leaves said carrying position for maintaining said automatic means operative without further manual assistance.

6. In combination, a hearse having sides, a door opening in one of said sides, a table mounted 70

upon a floor in said hearse, manually initiated automatic means for moving said table bodily laterally of the hearse, and simultaneously rotating said table and for thereby moving said table from a carrying position to a position where it projects laterally through said opening and for moving it from the latter position into the former position, and means operated by said table when it leaves said carrying position for maintaining said moving means operative without further manual assistance and for rendering it inoperative when said table is returned to said carrying position.

7. In combination, a hearse having sides, a door opening in one of said sides, a table mounted above a floor in said hearse, a turret projecting through said floor and in engagement with said table, a lateral slot in said floor through which said turret is laterally movable, a worm parallel to said slot, a nut on said worm so engaging said turret that lateral movement of said nut is transmitted to said turret, a rack parallel to said slot, a gear fixedly attached to said turret and in engagement with said rack and reversible driving means for said worm operating to either move said table from a carrying position parallel to the longitudinal axis of the hearse to a loading and unloading position where it projects laterally through said opening or to return said table from said loading and unloading position to said carrying position.

8. In combination, a hearse having sides, a door opening in one of said sides, a table mounted above a floor in said hearse, a turret projecting through said floor and in engagement with said table, a lateral slot in said floor through which said turret is laterally movable, a worm parallel to said slot, a nut on said worm so engaging said turret that lateral movement of said nut is trans-

mitted to said turret, a rack parallel to said slot, a gear fixedly attached to said turret and in engagement with said rack, driving means at each end of said worm operating to move said table in opposite directions, one of said driving means being adapted to move said table from a carrying position parallel to the longitudinal axis of the hearse to a loading and unloading position where it projects laterally through said opening and the other of said driving means being adapted to return said table from said loading and unloading position to said carrying position.

9. In combination, a hearse floor, a table and means thereunder for freely supporting the table on said floor, a pivotal support for said table, means for moving said support laterally without longitudinal movement and for rotating said table, said means comprising a worm and nut connected to said pivotal support for causing lateral movement thereof, and a rack and gear means for rotating said table.

10. In combination, a hearse having sides, a door opening in one of said sides, a table mounted upon a floor in said hearse parallel to the sides of the hearse and having ends adapted to project beyond the edges of said door opening, a pivot for said table disposed within the confines of said table, said table being so proportioned and so disposed with respect to said sides and door opening that it would strike one of said sides if rotated about said pivot, and means for rotating said table about said pivot and simultaneously laterally moving said pivot without longitudinal movement thereof in such manner as to project said table through said opening while preventing contact of the table with said sides.

HARRY A. TOULMIN, JR.
